REINFORCED PLASTER BASE

Lloyd F. Johnson, Wheaton, Ill., assignor to
United States Gypsum Company, Chicago, Ill.,
a corporation of Illinois

Application July 28, 1932, Serial No. 625,250

10 Claims. (CL 72—124)

This invention relates to building constructions, and has reference more particularly to plaster boards having joint reenforcing strips mounted upon the board at the time of shipment.

5 In erecting plaster boards, such as those made of vegetable fibers or a cementitious core composition with paper cover sheets, as gypsum board, it is customary to cover the joints between plaster boards with metallic reenforcing strips prior 10 to application of plaster, for the purpose of preventing cracks in the plaster at the board joints. It is preferable to have these strips attached to the plaster board at the time of shipment so as to reduce the amount of high priced labor necessary for erection at the job. However, the endeavor to market fiber boards with strips of metal mesh extending beyond the edge of the board has met with difficulty since the product is very difficult to pack for shipment, and furthermore, the overhanging metallic strips are apt to injure the hands of the workmen. The overhanging strips also make it difficult to nail the plaster board to the supporting studs.

An object of this invention, therefore, is to provide a plaster board having a reenforcing metallic strip slidably positioned adjacent an edge or edges of the board at the time of shipment.

Another object of the invention is to provide a 30 plaster board unit consisting of a plaster board with reenforcing strips attached to the face adjacent an edge and movable out of operative position so as to permit ready nailing of the plaster board to studding with a minimum of labor, and 35 also to permit easy packing and shipment.

A further object of the invention is to provide a plaster board reenforced unit in which a reenforcing strip is slidably attached to the face of the board so that it requires no further nailing 40 prior to the application of a coating of plaster; also to improve building constructions in other respects hereinafter specified and claimed.

Reference is to be had to the accompanying drawings forming part of this specification, in 45 which

Fig. 1 is a face view of a wall embodying the improved reenforcing means of the invention.

Fig. 2 is a sectional view through the wall construction taken on line 2—2 of Fig. 1.

Fig. 3 is a face view of a plaster board with the reenforcing strip in a position convenient for packing and shipment.

Fig. 4 is a sectional view through the plaster board taken on line 4—4 of Fig. 3.

Fig. 5 is a face view of a modified form of plaster board reenforcement.

Fig. 6 is a face view of a further modified form of plaster board reenforcement, and

Fig. 7 is a face view of a wall embodying the 5 reenforcing means shown in Fig. 6.

In Patent No. 1,740,493 to Birdsey and Manske, a reenforcing strip is proposed for use in reenforcing the joints of plaster boards, this strip being composed of two or more longitudinal wires 10 10 to which have been welded cross wires 11 which terminate in return bent hooks 12. Patent No. 1,768,127 to Manske and McNeil, describes a machine for making joint reenforcing strips of this nature.

I have discovered that reenforcing strips of the type described in these patents are especially adapted for use in forming plaster board units consisting of plaster boards of fiber or paper covered gypsum composition and reenforcing strips slidably attached to the face of the plaster board at the time of shipment. The plaster boards are preferably made of wood or other vegetable fibers, and may be provided with shiplapped longitudinal edges 13 which interlock, ends of the 20 board may be secured adjacent the board joints by nails 14 which are driven through the plaster board into a supporting stud 15. In order to attach the reenforcing strip to the plaster board prior to shipment, I provide staples 16, which 25 have legs 17 driven through the plaster board and terminate in points 18 which are clinched at the rear face of the plaster board. The staple 16 is spaced apart from the front face of the plaster board so as to slidably receive one of the cross 30 wires 11. The staple 16 is set back from the edge 35 of the plaster board so that during shipment and during the time that the boards are erected on studs 15 by driving the nails 14, the reenforcing lies out of operative position as shown in 40 Fig. 3.

After the boards are nailed to the studs, the reenforcing strip is moved transversely with the wires 11 sliding through the staples 16 so that the reenforcing strip overlies the longitudinal 45 joint as seen in Fig. 1. A plaster coat 20 is now applied over the plaster board, board joints and reenforcing strip in the usual manner. Owing to the fact that the strip lies flat after it has been moved into operative position due to the contact of hooks 12 on the inside of the staples 16, no further nailing of the reenforcing strip to the stud is required prior to the application of the plaster 20, although supplementary nailing of this nature may be used if desired. The boards 50

(Fig. 1) are usually arranged with their longitudinal joints extending horizontally, and with the board joints staggered. The reenforcing strip is usually only necessary along the longitudinal edges of the board, but they may be placed along the ends of the boards if desired.

In the preferred form of the invention, the staple 16 extends parallel with the edge of the board and with the reenforcing strip. In the modified form of construction shown in Fig. 5, the staples 16a may be turned at right angles to the reenforcing strip and edge of the board with the staple embracing one of the longitudinal wires 10. The staple 16a is preferably made somewhat longer than the staple 16 permitting sufficient sliding movement of the reenforcing strip so that it can lie in either the inoperative position shown in dot and dash lines in Fig. 5, or in the operative position shown by full lines in said figure. With this arrangement of the staple 16a, the reenforcing strip may be moved longitudinally as well as transversely into operative position so that the end of the strip overlies the corners of the boards to reenforce the corner joint.

While I have described the use of a reenforcing strip as disclosed in the aforementioned patents, any other suitable type of reenforcing strip may be used as long as it permits the sliding movement of said strip from inoperative to operative position. The plaster board unit which I have disclosed is convenient for packing and shipment of the plaster boards due to the fact that the reenforcing strips do not project beyond the edge of the board when they lie in inoperative position, and these units are also an advantage due to the fact that a free space is permitted for nailing the plaster board units directly to the studs without interference by the reenforcing strip. The plaster boards units are also an advantage in preventing injury to the hands of workmen during erection of the plaster board units as the strips have no edges projecting beyond the edge of the board when they lie in inoperative position. As an example of another type of sliding reenforcing strip which might be used, those shown in Figs. 6 and 7 are cited. In this type of strip, diagonally extending cross wires 23 are secured as by welding to longitudinal wires 24. Staples 25 engage the cross wires so that as the strips are moved transversely, they also automatically move longitudinally to cover the joints at the corners of the boards.

I would state in conclusion that while the illustrated examples constitute practical embodiments of my invention, I do not wish to limit myself precisely to those details, since manifestly, the same may be considerably varied without departing from the spirit of the invention as defined in the appended claims.

Having thus described my invention, I claim as new and desire to secure by Letters Patent:—

1. In a plaster board unit, a plaster board, a reenforcing strip positioned adjacent an edge of said board in a plane substantially parallel to the face of the latter, and staples connecting said strip to said board and securing the same in said plane, but permitting sliding movement of said

strip in said plane to permit said strip to lie in operative, overlapping position, or in inoperative position.

2. In a plaster board unit, a plaster board, a reenforcing strip positioned adjacent an edge of said board in a plane substantially parallel to the face of the latter, and means for attaching said strip to said board and securing the same in said plane, but permitting sliding movement of said strip in said plane. 10

3. In a building construction, a pair of boards in edge abutting relation, a stud, means for securing the edges of said boards to said stud, and a metallic reenforcing strip mounted on a board adjacent the edge thereof in a plane substantially parallel to the face of said board and arranged for sliding movement in said plane. 15

4. In a plaster board unit, a plaster board, a reenforcing strip positioned adjacent an edge of said board, and staples secured to said board parallel to the edge thereof and in spaced, parallel relation to the face of said board, a portion of said strip being slidably supported between said staple and the face of said board. 20

5. In a plaster board unit, a plaster board, a re-enforcing strip composed of longitudinal and cross wires, said strip being positioned adjacent an edge of said board, and staples secured to said board parallel to the edge thereof and engaging one of said cross wires to slidably secure said strip to 30 said board.

6. In a plaster board unit, a plaster board, a reenforcing strip composed of longitudinal wires and cross wires having hook ends extending beyond said longitudinal wires, and staples for slidably securing said strip to said board adjacent 35 a board edge.

7. In a plaster board unit, a plaster board, a reenforcing strip composed of longitudinal and cross wires, and staples secured to said board and 40 slidably connecting said longitudinal wires to said board edge.

8. In a building construction, a pair of plaster boards in edge abutting relation, a stud, means of securing the edges of said boards to said stud, a metallic reenforcing strip secured to one of said boards in a plane substantially parallel to the face of the latter and arranged for sliding movement in said plane over the joint between said boards, and a coating of plaster over said strip 50 and boards, said plaster serving to lock said strip against sliding movement.

9. In a plaster board unit, a plaster board, a re-enforcing strip composed of spaced longitudinal wires and diagonal cross wires, and staples secured to said board and slidably connecting said cross wires to said board so as to cause the longitudinal actuation of said strip as said strip is caused to move transversely. 55

10. In a plaster board unit, a plaster board, and a reenforcing strip connected to said plaster board in a plane substantially parallel to the face of the latter so as to be capable of both longitudinal and transverse sliding movement in said plane. 60

LLOYD F. JOHNSON. 65
